UNITED STATES PATENT OFFICE.

ANKER PETERSEN, OF WINTHROP, MASSACHUSETTS, ASSIGNOR, BY MESNE ASSIGNMENTS, TO ZENITH THREAD COMPANY, OF DETROIT, MICHIGAN, A CORPORATION OF MICHIGAN.

BRAIDING CARRIER.

Application filed August 16, 1922. Serial No. 582,160.

This invention pertains to braiding machines of that type having two series of bobbins revolving in opposite directions about a common axis and relates more particularly to carriers for bobbins of the inner series and to parts associated with such carriers. As herein disclosed, the invention is especially intended as an improvement upon the machine illustrated in the patents to Peter-
10 sen, No. 1,413,773, April 25, 1922 and No. 1,331,672 February 24, 1920.

Principal objects of the present invention are to provide a small and light weight carrier for the bobbins of the inner series comprising a minimum number of parts and which, when used in machines such as disclosed in the above patents will perform all the functions of the usual large and complicated carrier, as well as to provide parts 20 associated with such carrier for supporting and guiding it in its movements.

In the accompanying drawings a preferred embodiment of the present invention is illustrated by way of example and in such drawings;

Fig. 1 is a plan view of one half of a braiding machine of known type having the devices of the present invention applied thereto, certain parts being omitted for the sake of clearness of illustration;

Fig. 2 is a vertical diametrical cross section taken substantially on the plane of line 2-2 of Fig. 1, the carriers being shown in elevation;

Fig. 3 is a plan view of an improved form of bobbin carrier made in accordance with the present invention;

Fig. 4 is an edge view of the carrier of Fig. 3 viewed from the right hand side of such figure;

Fig. 5 is a vertical cross section on the line 5-5 of Fig. 3, omitting the bobbin tension plate.

Fig. 6 is a vertical cross section on the line 45 6-6 of Fig. 3;

Fig. 7 is a fragmentary vertical cross section on the line 2-2 of Fig. 1 but to larger scale, the carrier being shown in elevation;

Fig. 8 is a fragmentary detail view illustrating a detector device forming an element of the carrier; and

Fig. 9 is an elevation illustrating in detail a wheel employed for supporting the carrier.

Referring to the drawings, the numeral 1 indicates a rotating support comprising a cylindrical portion 2 forming a ring-like member upon which the carriers for the outer series of bobbins are mounted, such carriers not being illustrated herein. A table 3 is arranged concentrically with the member 1 and is caused to rotate oppositely to the latter member in any desired manner known to the art. Upon the table 3 a series of frames 4 are mounted which provide journals for the shafts of drive rolls 5. These rolls are preferably provided with enlarged hub members 6 formed from felt or other suitable friction material. A stationary supporting disc 7 is arranged concentric with the ring member 2 having a series of resilient fingers projecting radially from its edge. These fingers serve to support a ring 9 formed from rubber, felt or other suitable material which bears against the several hubs 6 of the drive rolls, causing such rolls to rotate on their axes as the table 3 is turned.

The support 7 is provided at its outer edge with a rib 10 providing a track for the inner supporting rolls of the carriers hereinafter to be described. The inner peripheral surface of the cylindrical or ring-like member 2 is provided with a circumferential groove 11 having a lower substantially horizontal wall 12 and an upper wall 13. A substantially continuous ring or plate 14 of some material having good electrical conducting properties, such for example as brass, is secured to the inner surface of the ring 2 above the groove 11, suitable insulating material 15 being interposed between the ring 14 and the inner surface of the member 2. One section of this ring 14 is removably secured in position to permit the carriers to be assembled with or removed from the ring 2. The lower edge of the ring or plate 14 projects downwardly and overlaps the upper face 13 of the groove 11 as indicated at 16.

The carriers of the inner series of bobbins consist of open frames comprising the substantially parallel side members 17, 18, the inner end member 19 and the outer end member 20. At the junction of the members 17 and 18 with the outer member 20, laterally projecting ears 21, 22 are provided, these ears being slotted horizontally

for the reception of supporting wheels 23, 24. Each of these wheels, as shown in detail in Figs. 6 and 9, comprises an annular rim member 24^a with which is secured a ring 24^b forming one element of a ball race. A second annular member 25 is arranged concentrically with the member 24^b forming the complementary member of the ball race, and between the parts 24^b and 25 a series of ball bearings 26 are arranged. The wheels 23, 24 are mounted in the slots in the ears 21, 22 by means of the pins 27 fixed in the inner members 25 of the respective wheels and secured in openings in the ears. The inner end member 19 of the carrier is provided with an apertured boss 28 within which a pin 29 provided with an axial bore 32 is secured. This pin projects beyond the boss and supports anti-friction bearings of the type just above described upon which a wheel or roll 30 provided with a beveled peripheral face 31 is mounted. The beveled surface 31 of the wheel 30 rests upon the upper face of the rib 10 above described, while the lower faces of the wheels 23 and 24 rest upon the bottom wall 12 of the groove 11 in the part 2. The carrier is thus supported upon anti-friction bearings at three points for movement in a circular path. Projecting upwardly from the outer member 20 of the carrier are two pairs of ears 33, 34 respectively and between the respective ears of said pairs retaining rolls 35, 36 are journalled upon suitable supporting pins. When the carrier is properly positioned these rolls lie within the groove 11 and project upwardly behind the lower edge 16 of the plate 14. This plate, in cooperation with these rolls, thus serves to prevent inward radial movement of the carriers and holds the carriers in proper relative relation to the ring 2 and the support 7. The outer member 20 of the carrier is provided with a vertical slot 37 for the reception of a wheel or roll 38 mounted upon a pin 39 and of a diameter such that its lower peripheral element lies in a plane below the plane of the upper peripheral elements of the drive rolls 5. With this arrangement rotation of the member 3 causes the drive rolls 5 to push the several carriers ahead of them, causing the carriers to revolve about the axis of the machine in the usual manner.

Each of the side members 17, 18 of the carrier is provided with a vertically elongate bearing slot 40 having a lateral opening 41 adjacent to its lower end and having the overhanging side wall 42. These bearing slots receive the opposite ends respectively of a bobbin spindle 43 which may be placed within the slots 40 by inserting them laterally through the openings 41. A bobbin 44 is indicated as mounted upon the

spindle 43. The upper surfaces of the side members 17 and 18 are inclined downwardly toward the lateral openings 41 in the bearing slots 40 to guide the ends of the bobbin spindle as the bobbin is placed in 70 operative position.

A plate 45 is secured to a sleeve 45^a journalled to turn relatively to the side members 17, 18 and having an adjustable tension spring 46^b normally tending to turn it in a 75 counterclockwise direction as viewed in Fig. 4. This plate preferably terminates in a series of parallel resilient fingers 46 which extend below the bobbin and which serve to support the latter. The spring 46^b is normally tensioned sufficiently to support the weight of the bobbin resting upon the fingers 46 and to cause the ends of the bobbin spindle to occupy the upper portions of the slots 40. With this arrangement the weight 80 of the bobbin rests upon the fingers 46, providing a braking effect tending to retard rotation of the bobbin and thereby exerting the desired tension upon the yarn Y as the latter is drawn off from the bobbin. As the bobbin decreases in size, the frictional resistance to turning gradually decreases at 85 substantially the same rate that the leverage exerted by the yarn in turning the bobbin is decreased, but it is evident that there is no 90 possibility that the tension will be entirely relieved at any time as is common where the tension spring is merely caused to bear upon the upper surface of the bobbin. The yarn 95 from the bobbin passes through the opening 32 in the pin 29 and from thence to the braiding point, so that special guide means therefor is unnecessary.

The members 17, 18 of the carrier are provided with aligned bearing openings 47, 48 respectively for the reception of the oppositely directed ends 49, 50 of a bail-like detector finger comprising the shaft 50^a, the parallel members 51 and 52 and the transverse member 53. This detector finger is 105 conveniently formed from wire suitably bent and is so arranged that its transverse member 53 lies parallel to the axis of the bobbin and is substantially coextensive in length with the thread mass upon the bobbin 110 spindle. A spring 54 surrounds the shaft 50^a and tends normally to move the detector member outwardly and away from the bobbin and into contact with the inner surface 115 of plate 14, this action of the spring being normally opposed by the tension of the yarn which passes over the member 53 on its way to the opening 32. The entire frame of the carrier, as well as the wheels 24, is 120 preferably formed of metal or other suitable electrical conductor, but the retaining rolls 35 are of some insulating material such as indurated fibre or the like. As the detector 125 53 is also of metal and is supported in openings in the metallic members 17 and 18, the 130

detector is always connected electrically with the ring member 2. The machine is preferably provided with some form of electrical stop motion, such as shown for example in the patent to Petersen, No. 1,072,984, September 9, 1913, and the ring 2 and the plate 14 constitute poles of the electrical circuit of this stop mechanism. When during operation one of the yarns break, the corresponding detector finger immediately moves outward into contact with the plate 14, thus completing the circuit and stopping the machine in a manner well known in the art. As thus arranged, the carrier may be mounted upon anti-friction bearings so that it moves with the greatest freedom, while the stop motion circuit is completed without necessitating the employment of a brush or similar element which would retard the free movement of the carrier. Moreover, when the device herein shown is employed in a machine of the kind shown in the patent to Petersen, No. 1,413,773 above referred to, it is unnecessary to provide a detector for indicating exhaustion of the thread upon the bobbin as the measuring apparatus disclosed in such patent may also be relied upon to stop the machine when the yarn carried by the bobbins of the inner series has been exhausted. The carrier as thus constructed is extremely light in weight and of simple construction and by arranging the bobbin in the manner shown so that its spindle is perpendicular to the central radial line of the carrier, it is possible to decrease the usual stroke of the thread lever for the outer series of bobbins, thus minimizing the vibration of the parts and making it much easier to keep the machine in operative condition.

As above stated, the spring fingers 46 not only constitute tension means, but also serve to support the bobbin in operative position, thus permitting the employment of the slots 40 with their lateral openings 41 which allow the ready insertion in and removal of the bobbins from the carriers without necessitating the manipulation of catches or other retaining means. As a further element of simplicity in the structure, the double function of the plate 14 may be mentioned, such plate not only serving as retaining means for the carriers but also as one of the elements of the electrical circuit.

What I claim and desire to secure by Letters Patent of the United States is:

1. A braiding machine comprising a carrier having a frame, said frame being provided with vertically elongate bearing slots for the ends of a bobbin spindle, and a resiliently and pivotally supported member carried by the frame, said member being inclined to the horizontal and having its lower end disposed below the bobbin thereby constituting the sole support for the latter.

2. A braiding machine having in combination a carrier provided with vertically elongate journal slots for a bobbin, said slots having lateral entrance openings, and resilient means for retaining the bobbin in operative position within the journal slots, said resilient means being movable only in a predetermined path and being constructed and arranged to support and to guide the bobbin while the latter is being advanced into operative relation to the journal slots.

3. A braiding machine having in combination with a carrier provided with vertically elongate guideways for the ends of a bobbin spindle, said guideways having lateral entrance openings, and a member resiliently supported to swing about an axis parallel to that of the bobbin spindle, said member engaging the peripheral surface of the bobbin and thereby supporting the latter, said member being so constructed and arranged as to guide the bobbin during the introduction of the spindle ends through said entrance openings into said guideways.

4. A braiding machine having in combination a carrier provided with vertically elongate bearing slots in which the opposite ends respectively of a bobbin spindle may turn freely, said slots have lateral entrance openings, guides inclined downwardly toward said entrance openings, and resilient means normally supporting the weight of the bobbin by engagement with the peripheral surface of the latter, said resilient means comprising a member pivotally mounted to turn about an axis, transversely spaced from the axis of the bobbin spindle.

5. A braiding machine comprising a carrier having vertically elongate slots for the reception of the opposite ends of a bobbin spindle, one at least of said slots having a lateral entrance opening, and a pivoted plate divided at its free end to form a series of resilient fingers constructed and arranged to underlie and to constitute the sole support for a thread mass mounted upon the spindle.

6. A braiding machine having in combination a carrier comprising an open frame having parallel side members, each of said members having a vertically elongate bearing slot provided with a lateral opening adjacent to its lower end for the insertion of a bobbin spindle, and a pivotally supported plate underlying the peripheral surface of the bobbin, said plate having spaced bobbin engaging elements and resilient means normally retaining said plate in position to support the weight of the bobbin.

7. A braiding machine comprising a carrier arranged to move in a horizontal, circular path, a pair of supporting wheels at the outer end of the carrier arranged to turn about vertical axes, and a supporting wheel at the inner end of the carrier turning about a substantially radial axis, bearing

ings for said wheels, the bearing for the inner wheel having a central opening therethrough for the passage of the thread.

8. A braiding machine comprising a carrier arranged to move in a circular path, a bobbin supported by the carrier and a supporting wheel for said carrier, said wheel comprising a rim member, and an annular hub member, said latter member constituting 10 an element of a ball race, a second annular member fixed to the carrier and concentric with said first annular member, said second member constituting the other element of the ball race, and a series of balls interposed 15 between said annular members, the thread from the bobbin passing through said annular hub.

9. A braiding machine comprising a braiding carrier moving in a circular path, 20 said carrier having means for supporting a bobbin with its axis perpendicular to the central radial line of the carrier, a thread break detector pivoted to the carrier to swing about an axis parallel to that of the bobbin 25 and having a thread engaging element ex-

tending longitudinally of the bobbin and substantially coextensive in length therewith, and spring means normally tending to move said detector in opposition to the tension of the thread.

10. A braiding machine having in combination a braiding carrier comprising an open frame provided with oppositely disposed aligned bearings for a bobbin spindle, a detector member having elements pivotally supported in bearing openings parallel to the bobbin spindle bearings respectively and an elongate member extending longitudinally of the bobbin and substantially co-extensive 35 in length therewith and parallel with the axis thereof for engagement with the thread as it is drawn from the bobbin, and spring means normally tending to move said detector member in opposition to the tension of the thread whereby to complete an electrical 40 circuit upon breakage of the thread.

Signed by me at Boston, Massachusetts, this ninth day of August, 1922.

ANKER PETERSEN.
